UNITED STATES PATENT OFFICE.

DEMETRY MINDELEFF, OF SAN FRANCISCO, CALIFORNIA.

PROCESS OF EXTRACTING NICKEL AND COBALT FROM ORES.

SPECIFICATION forming part of Letters Patent No. 354,923, dated December 28, 1886.

Application filed September 3, 1885. Serial No. 176,116. (No model.)

To all whom it may concern:

Be it known that I, DEMETRY MINDELEFF, of San Francisco, State of California, have invented a new and Improved Process of Extracting Nickel and Cobalt from Ores Containing Them, of which the following is a specification.

This invention relates to the extraction of the above-named metals from the ore in its condition as it is taken from the mine; and it consists in treating it in its lump state with hydrocarbon gas in a heated chamber, then pulverizing it, and finally extracting the metallic particles from the gangue by dipping an electro-magnet into the ore as it is agitated as a pulpy mass in a tub, the magnet being periodically withdrawn to deposit the adhering particles in a separate store.

In the accompanying drawings, forming a part of this specification, Figure 1 is a sectional elevation of the apparatus used in carrying my invention into practice, Fig. 2 being a plan of the same.

In both figures the same letters of reference are used to indicate the same parts.

According to the invention the ore in its lump state is placed in the retort A, which may be of any suitable size and shape, and therein it is heated in the furnace B to a red heat. There is then passed into the retort a quantity of hydrocarbon gas sufficient to reduce all of the metals before named which may be contained in the ore, the quantity varying according to the richness of the ore, being determined by means hereinafter described.

The gas need not be purified, and may be obtained from wood, naphtha, coal, or other substance yielding it by the ordinary process of dry distillation. It may be stored in the gas-holder C, which may be made like those ordinarily used for storing illuminating-gas.

The retort is provided with an induction-pipe, D, at one end and an eduction-pipe, D', at the other end. This latter pipe dips into a condenser, E, a common wooden tub covered and partly filled with water.

Branching from the eduction-pipe there is a testing-pipe, D'', with a stop-cock on it. This is used for periodically testing for the presence of arsenical or sulphureted hydrogen gas, for as long as either of these gases is evolved the reduction of the metals is not complete,

and the hydrocarbon gas must continue to be passed into the retort. In testing, the end of the pipe D'' is immersed in a solution of copper or lead held in the test-tube F, when, the cock on the test-pipe being opened, the presence of the evolved gases named is detected by a black precipitation following their mixing with the solution. As soon as the precipitation ceases it is known that the metals in the ore are properly reduced, and the hydrocarbon gas may be shut off from the retort and its contents be left to cool, enveloped in an atmosphere of the gas. The vapors and gases passing out of the retort are mostly condensed in the condenser, the residuum being periodically drawn off by the cock e at the bottom. What little hydrocarbon gas escapes from the retort unconsumed will pass out of the condenser through the overflow-pipe G back into the gas-holder. The retort having been withdrawn from the fire, or vice versa, as the case may be, and its contents having sufficiently cooled, so as to be handled, they are next taken to the crushing-rolls H, where the ore is finely pulverized, the finer the better. There is nothing peculiar about these rolls. Any suitable style will do. All that is necessary is, that there shall be no coarse particles left un-crushed; otherwise an ordinary rock-breaker might be substituted for the rolls, or even a stamp-mill would do. From the crushing-mill the pulverized ore is taken to the separator I, and in that machine it is mixed with a quantity of water sufficient to give the mass the consistency of thin mud. This separator and agitator combined is a novel machine, and needs to be described in detail.

J is a common wooden tub. K is a spindle standing upright in the middle and resting in the step N and bearing N'. From this spindle there radiate a number of arms, L, which stir up the pulpy mass as the spindle is revolved by the bevel gear-wheels M on top, which transmit motion from the horizontal shaft O.

P is the soft-iron core of an electro-magnet. This is enveloped with an insulated electric coil, P', which connects with the conducting-wires Q through the swinging bar R, having a roller, r, on its lower end. There is a metal track, S, for the roller of the swinging bar to traverse during the time the electric current

is maintained through the coil, to which track the conducting-wires are connected.

T is a horizontal shaft with a cam or arm, U, secured upon it, which cam has a roller, U', on its end.

V is a wooden frame surrounding the magnet, which frame has a projecting limb, Y', and is held constantly in a perpendicular position by sliding against the stationary frame.

- o work of the machine, against which it is drawn by means of a counterbalance-weight, W, connected to the lower end of the frame V by a cord passing over the pulleys w w. The shaft T is revolved by pulley-and-belt connection 5 with the shaft O. There is a pivot, X, projecting from each side of the frame of the magnet, which pivot, resting on the frame of the apparatus when the magnet, having been raised to its highest point, is being drawn o back to deposit the particles adhering to it in the storing-box Y, supports the magnet at its highest point after the cam has passed by and ceased to do so.

The frame-timbers will have notches cut out 5 at x to permit the pivots to pass as the magnet is raised.

The operation of this combined separator and agitator is as follows: The pulpy mass is vigorously stirred up by the revolving arms o in the tub. The magnet in its normal position, as in full lines, Fig. 1, receives the electric current, and the core being thus magnetized collects on its surface all the metallic particles coming in contact with it. The cam 5 in revolving lifts the magnet periodically out from the pulpy mass until it is high enough to pass over the rim of the tub. Then the cam draws it back far enough to bring it over the storing-box Y, when, the roller r of the swing- o ing bar R having left the track S, the current of electricity is broken, the core is no longer magnetized, and the adhering particles of metal drop off into the box. The cam at this

time has escaped contact with the arm of the magnet-frame, and there being nothing to hold 45 the magnet the counter-weight comes into action and draws the magnet back to again drop it into the agitator, the operation being repeated until the metals are all extracted.

The different positions of the magnet during the operation are shown in dotted lines, Fig. 1.

I am aware that it is not new to separate nickel from reduced ore by the aid of electromagnets, and also that it is not new to deoxidize 55 and metallize iron ore by first superheating it in a granulated state and then suddenly discharging it into a chamber containing pulverized carbon, finally separating the metallic particles by the aid of a magnetic separator. 60 I do not, therefore, claim originality with respect to all the distinct stages of my process, separately considered, but only with respect to all of them, when combined and constituting a complete system in itself for extracting 65 the metallic particles from the ore originally in a lump state.

I therefore claim as my invention, and desire to secure by Letters Patent, as follows:

The herein-described process of extracting 70 the metallic particles of nickel and cobalt from the ore containing them, consisting of a combination of the following operations in the order named: first, treating the lump ore with hydrocarbon gas in a closed and heated chamber, then in reducing the ore to a pulverulent state, then in mixing the mass with water until it acquires a pulpy consistency in a suitable agitating-machine, and finally extracting the metallic particles from the pulpy mass by the 80 aid of any suitable electro-magnetic separator, substantially as set forth.

DEMTRY MINDELEFF.
